UNITED STATES PATENT OFFICE

109,813

DESIGN FOR A COMBINED WASHING MACHINE AND WRINGER

John R. Morgan, Oak Park, Ill., assignor to Sears, Roebuck and Co., Chicago, Ill., a corporation of New York

Application January 15, 1937, Serial No. 67,070

Term of patent 3½ years

To all whom it may concern:

Be it known that I, John R. Morgan, a citizen of the Republic of Guatemala, residing at Oak Park, in the county of Cook and State of Illinois, have invented a new, original, and ornamental Design for a Combined Washing Machine and Wringer, of which the following is a specification, reference being had to the accompanying drawing, forming a part thereof.

Fig. 1 of the drawing is a perspective view of a combined washing machine and wringer, embodying my new design.

Fig. 2 is a similar view of the same, taken from a different angle.

I claim:

The ornamental design for a combined washing machine and wringer, as shown.

JOHN R. MORGAN.
